UNITED STATES PATENT OFFICE.

IVAR RENNERFELT, OF DJURSHOLM, SWEDEN.

ELECTRIC FURNACE.

1,313,834.

Specification of Letters Patent.

Patented Aug. 19, 1919.

Application filed May 12, 1919. Serial No. 296,591.

To all whom it may concern:

Be it known that I, IVAR RENNERFELT, a citizen of the Kingdom of Sweden, and resident of Djursholm, in the county of Stockholms Län and Kingdom of Sweden, have invented certain new and useful Improvements in Electric Furnaces, of which the following is a specification.

My invention relates to improvements in the construction of an electrically heated crucible furnace and has for its object to provide a furnace especially suitable for utilizing electric arcs for melting metals, glass, enamels and other materials in crucibles or melting pots.

To obtain this object I propose to arrange vertical or nearly vertical electrodes in a plane in the center of a furnace room, the electrodes being practically parallel to each other. Arcs burning between the lower ends of the electrodes and an elongated conducting bed underneath, projecting from the bottom of the furnace room, generate an intense heating zone, emitting heat to both sides. Crucibles or glass melting pots to be heated are placed on one or preferably both sides of and along the heating zone. The rays of heat strike the crucibles not only directly but also indirectly by reverberating downward from the roof, if a proper curvature is given to this. The central conducting bed underneath the electrodes should preferably be made of a block of carbon or graphite supported on a projection of carborundum or other very refractory material. To protect the contact block from being oxidized or volatilized it may be covered with a quantity of preferably pulverized graphite or carbon. The presence of the powder also promotes smooth burning of the arcs by introducing a considerable resistance in series with the arc. The number of electrodes depends principally on the nature of the current, but also on the size of the furnace. When utilizing three phase current the number of electrodes should preferably be three, but if the furnace room is rather long, the number of electrodes may be a multiple of three. In the case of two phase current the number of electrodes is two or a multiple of two. If the furnace is run with single phase or direct current, the power may be divided on two or more electrodes.

To facilitate introduction or removal of the crucibles openings are to be provided at

one or both ends of the furnace room. If the length of this is rather great, openings may be provided also in the other sides of the furnace room, one for each crucible.

60

If glass is to be melted for blowing purposes, openings are provided in the side walls slightly above the crucibles for the introduction of the glass blower's pipe.

The shape of the crucible may be rectangular, oval or round or of any form preferred. Special openings, one at each end of the furnace room, permit replacement of the carbon block contact, when this is required for any certain reason. Such parts of the walls, which are especially exposed to an excessive heating from the arcs, are to be protected by blocks of carborundum, zirconia or other suitable material.

According to a modification of the invention the electrodes, if considerably more than three are used, may be arranged, not in a plane, but in a curved surface, for instance on a cylinder. The crucibles are in such a case to be arranged on the outside of the cylinder of the electrodes, between this and the cylindrical wall of the furnace. To provide contacts for the arcs a centrally located projection from the bottom is covered with carbon in any preferred form. To facilitate removing of the crucibles from the furnace openings corresponding to each crucible must be provided in the cylindrical wall of the furnace. Other openings slightly above aforesaid openings permit the introduction of glass blowers' pipes or other tools if necessary.

A furnace built according to the present invention is illustrated on the accompanying drawing, in which Figure 1 is a vertical section taken at lines $y-y$ in Fig 2, which is a horizontal section taken at lines $x-x$ in Fig. 1. A modified form of a furnace is illustrated by Fig. 3, which is a horizontal section of a circular furnace. Similar letters refer to similar parts in the several views.

Vertical or nearly vertical electrodes 1 are projected from above through a roof 2 into a furnace room. A projection 3 from the bottom 4 of the furnace supports a block 5 of carbon or graphite and on top of this a quantity 6 of pulverized carbon or graphite, which affords contacts for the arcs 7 from the electrodes. The electrodes are placed on a line one after the other as indicated in Fig. 2 or in a circle as in Fig. 3. In the

former case a plane heating zone is generated, in the latter case a circular or, rather, cylindrical heating zone. Rays of heat 8 emanate from the heating zone toward crucibles or melting pots 9 located between the heating zone and the surrounding furnace wall.

To remove said crucibles openings 10 are provided in the wall. Other openings 11 10 slightly above the openings 10 permit the introduction of tools such as glassblowers' pipes or the like.

The contact block 3 may be replaced through a door 12 through which the contact powder may also be replaced. By properly shaping the curve of the inside of the roof the heat-rays from the arcs, which are going upward, may be made to reflect downward into the crucibles as in ordinary 15 reverberatory fuel heated furnaces. The furnace in Fig. 2 has only two crucibles on each side of the electrodes but the number of crucibles may be greatly increased by increasing the length of the furnace and the 20 number of the electrodes correspondingly.

Having now fully described my invention, I claim:

1. In an electric furnace the combination

of a plurality of electrodes suspended from above into a furnace room in a substantially vertical plane, a projection from the bottom of the furnace room underneath the electrodes, a conducting layer of carbon in suitable form on the said projection forming contacts for arcs from the electrodes and crucibles on the bottom of the furnace, along 30 the heating zone of the arcs.

2. In an electric furnace the combination of a plurality of electrodes suspended from above into a furnace room in a substantially 35 cylindrical surface, a projection from the bottom of the furnace room underneath the electrodes, a conducting layer of carbon in suitable form on the said projection forming contacts for arcs from the electrodes, 40 crucibles in the space surrounding the cylindrical heating zone and openings in the furnace wall corresponding to each crucible.

Signed at Stockholm in the county of Stockholms Län and State of Sweden this 50 15th day of April, A. D. 1919.

IVAR RENNERFELT.
